AIR-POWERED PRESS WITH AUTOMATIC PRESSURE RELEASE

Herbert M. Robinson, 3591 W. Outer Drive, Detroit 21, Mich.; Fay Robinson, administratrix of said Herbert M. Robinson, deceased

Filed Dec. 22, 1958, Ser. No. 782,048
6 Claims. (Cl. 121—38)

This invention relates generally to improvements in air-powered presses and, in particular, to an air-powered press including an improved control means and lever operating structure.

It is the primary object of the present invention to provide an improved air-powered press including an air cylinder and an automatic control means for controlling the admission and exhaustion of air from said cylinder at any pre-determined point during the operation of the press with full power being available and exerted by the cylinder up to said point.

It is another object of the present invention to provide an improved air-powered press which is compact in construction whereby a shorter air cylinder may be used and a greater mechanical advantage is obtained than in similar presses made heretofor.

It is a further object of the present invention to provide an improved air-powered press including an air cylinder having an air flow control valve mounted in close proximity to the air cylinder and which valve may be hand or foot operated in one direction to admit air into the cylinder, and automatically operated in the other direction to release the air from the cylinder by control means operated in accordance with the travel of the piston rod of the cylinder.

It is still another object of the present invention to provide an improved air-powered cylinder having a novel air cylinder and control means and which is simple and rugged in construction, economical of manufacture and efficient in operation.

Other objects, features and advantages of this invention will be apparent from the following detailed description and appended claims, reference being had to the accompanying drawings forming a part of the specification wherein like reference numerals designate corresponding parts of the several views.

In the drawings:

FIG. 1 is a vertical side elevational view, partly in section, of an air-powered press made in accordance with the principles of the present invention;

FIG. 2 is a fragmentary side elevational view of the operating levers of the air valve used in the present invention and showing them in one operative position;

FIG. 3 is a top plan view of the structure illustrated in FIG. 1, taken in the direction of the arrows marked 3;

FIG. 4 is a fragmentary right side elevational view of the structure illustrated in FIG. 1, taken in the direction of the arrow marked 4;

FIG. 5 is a fragmentary elevational sectional view of the structure illustrated in FIG. 1, taken substantially along the line 5—5 thereof;

FIG. 6 is a partial elevational side view of the press illustrated in FIG. 1 but showing a modified control system for the air cylinder; and,

FIG. 7 is a fragmentary elevational sectional view of the structure illustrated in FIG. 6, taken substantially along the line 7—7 thereof.

Referring now to the drawings, and in particular to FIGS. 1 through 5, the numeral 10 generally designates the C-shaped body of the air-powered press of the present invention. The body 10 includes the lower or base

2

portion 11 provided with the laterally extended bottom jaw 12, and the vertical column portion 13 which carries the laterally extended upper jaw 14. The body base portion 11 is provided with the usual attachment pads 15 through which are formed the holes 16 for attaching the press in place.

As shown in FIG. 1, the bottom jaw 12 functions as an anvil sleeve in which is threadably mounted the threaded stud 17 which functions as an anvil. The stud 17 is slotted longitudinally as at 18 and is guided by means of the screw 19 projecting into the slot 18. The stud 17 is adjustably locked in place by means of the lock nuts 20. A conventional push rod 21 is slidably mounted in the vertical hole 22 in the upper jaw 14 and is provided on the lower end thereof with the socket 23 for the reception of a work tool, such as a punch or riveting tool. The work tool would be held in place in the socket 23 by means of a suitable set screw as 24. The push rod 21 is provided with the vertical slot 26 in which is slidably engaged the inner end of the screw 25 whereby the push rod is guided for vertical movement.

A pressure link 27 is provided for moving the push rod 21 upwardly and downwardly. The pressure link 27 is pivotally connected at the lower end thereof to the upper end of the push rod 21 by any suitable means, as by means of the pivot pin 28. The upper end of the pressure link 27 is suitably pivotally connected at the upper end thereof to the front end of the rocker arm 29 by any suitable means, as by means of the pivot pin 30.

As shown in FIGS. 1 and 3, the rocker arm 29 is pivotally mounted at the forward end thereof between the upwardly extended arms 31 and 32 by means of the pivot pin 33. The rocker arm 29 is pivotally connected at the rear end thereof to the front end of the toggle link

34 by means of the pivot pin 35. The rear end of the toggle link 34 is pivotally connected by means of the pivot pin 36 to the outer end of the first or short arm of the bell crank, generally indicated by the numeral 38. The bell crank 38 also includes the second or longer arm 39, the upper end of which is hingedly mounted between a pair of stationary arms as 41 by means of the pivot pin 40. The arms 41 are fixed on the upper outer rear end of the body column portion 13. The lower end of the bell crank arm 39 is pivotally connected by means of the pivot pin 42 to the outer end of the cylinder rod 43 of the air cylinder, generally indicated by the numeral 44.

As shown in FIGS. 1, 3 and 4, the air cylinder 44 includes the cylinder or tubular body 45 which is enclosed on the lower end thereof by the piston head end cover 50 member 46 and at the upper end thereof by the cylinder rod end cover member 47. The cover members 46 and 47 are fixedly secured to the cylinder 45 by means of the elongated bolts 48 and the nuts 49. The cylinder end cover 46 is provided with the downwardly extended integral arm 50 which is disposed between the spaced apart upwardly extended arms 51 and 52 on the body base portion 11. The arm 50 is pivotally connected to the arms 51 and 52 by means of the pivot pin 53.

As shown in FIG. 1, the cylinder rod 43 is slidably mounted in the bushing 54 which is suitably mounted in the hole 55 formed through the cylinder end member 47. The top cylinder end member 47 is provided with the vent hole 56 in which is mounted the vent screen 57. Slidably mounted in the cylinder 45 is the piston 58. The reduced inner end 59 of the cylinder rod 43 is mounted through the hole 60 in the piston 58 and is secured thereto by means of the nut 61 which is seated in the enlarged outer end 62 of the hole 60. The piston 58 is provided with the oil wick 63 which is mounted in a suitable annular groove and with the seal member 64 which is also mounted in a suitable annular groove. The piston 58 is normally

retained in the inoperative position shown in FIG. 1 by means of the return spring 65, the lower end of which is seated in the annular groove 66 formed in the inner face of the piston 58 and the upper end of which is seated in the annular groove 67 formed in the inner face of the cylinder end cover member 47.

As shown in FIG. 1, the bottom end cover of the cylinder is provided with the air passage 68 which communicates with the interior of the cylinder 45. Mounted in the outer end of the passage 68 is the tubing fitting 69 in which is mounted one end of the tubing 70. The other end of the tubing 70 is mounted in the tubing fitting 71 which is mounted in a first port 72 in the air flow control valve generally indicated by the numeral 73. It will be seen that the valve 73 is mounted on the press body in a position adjacent the air cylinder 44. The control valve 73 includes the rear body portion 74 and the front body portion 75 which are secured together by a plurality of body cap screws as 77 and between which is mounted the body gasket 76. As shown in FIG. 5, the control valve 73 is secured to the press body 10 by means of the spacer sleeves 78 and the screws 79 and nuts 80.

A chamber 81 is formed in the front valve body portion 75 and movably mounted in this chamber is the control plate 82. The control plate 82 is fixedly mounted on the inner end of the valve operating plunger 83 and this plunger extends outwardly of the valve body portion 75 through the boss 84. The plunger 83 is provided with a suitable seal as 85. An exhaust conduit 86 is formed in the rear valve body portion 84 and communicates with a chamber 81, and this exhaust conduit is adapted to be closed by means of the exhaust valve 87 which is carried on the control plate 82. The control plate 82 also carries the fixed intake valve rod 88 which is adapted to unseat the intake valve 89 when the operating plunger 83 is moved inwardly of the valve body. The intake valve is disposed in the intake passage 91 and is normally biased to a closed position to the left as viewed in FIG. 1, by means of the spring 90. Fixedly mounted in the outer end of the intake passage 91 is the intake passage cap 92 which is adapted to be connected to any suitable source of air under pressure. The foregoing described structure is a conventional valve available on the market. A suitable valve for the purposes of this invention is a treadle valve, model F-61, and obtainable from the Robinson Engineering and Sales Co., Detroit, Michigan.

The numeral 93 indicates an operating pedal which may be adapted for hand or foot operation and which is connected to the first valve control lever 94 by any suitable means, as by the screw 95. As shown in FIGS. 1, 3 and 5, the lever 94 is pivotally mounted on the stationary post or pivot pin 96 which is fixed on the press body column 13 by means of the screw 97 and nut 98. The lever 94 is adapted to be held in the inoperative position shown in FIG. 1 by means of the return spring 99. One end of the spring 99 is connected to the bracket 100 which is fixed by means of the screw 101 to the press body. The other end of the spring 99 is secured to the pivot pin 102 which is carried on the upper end of the lever 94 and which extends sidewardly, outwardly therefrom. A trip bar 103 is pivotally mounted on the pin 102 and the rear end thereof is adapted to be normally engaged in the notch 104 formed on the upper end of the second valve control lever or plunger lever 105. The lever 105 is disposed adjacent the lever 94 but is spaced apart therefrom and is also pivotally mounted at an intermediate point thereof on the pivot pin 96. The lower end of the lever 105 is pivotally mounted to the outer end of the valve operating plunger 83 by any suitable means, as by means of the pivot pin 106. The lever 105 is adapted to be normally held against the trip bar 103 by means of the return spring 107. The spring 107 is secured to the upper end of the lever 105 as at 108, and to the valve body 10 as at the point 109.

As shown in FIGS. 1, 3 and 5, a bracket 110 is fixedly

secured by means of the screw 111 to the rocker arm 29. The bracket 110 includes the lower outwardly extended horizontal arm 112 which may be termed a fork arm and which is provided with the slot 113 into which is engaged the vertical control rod 114 when the rocker arm 29 is moved about its pivot pin 33 in a counterclockwise direction as viewed in FIG. 1. An adjustable stop member 115 is secured on the upper end of the rod 114 by means of the set screw 116. The rod 114 is slidably mounted through the hole 117 in the boss 118 which is mounted on the upper end of the press body 10. The lower end of the rod 114 is slidably mounted through the vertical hole 119 in the bracket 120 which is fixedly secured to the press body wall 13 by means of the screws 121 and nuts 122. An adjustable stop 123 is mounted on the rod 114 by means of the set screw 124 and this stop limits the downwardly movement of the rod 114 relative to the bracket 120. A trip lever 125 is pivotally mounted on the lower bifurcated end of the bracket 120 at an intermediate point thereof as at 126. A stop member 127 is mounted on the extreme lower end of the rod 114 and a spring 128 is mounted on the rod 114 between the bracket 120 and the trip lever 125. The spring 128 functions to normally press the inner end of the lever 125 downwardly which in turn forces the stop 127 and the rod 114 downwardly. Adjustably mounted on the outer end of the trip lever 125 is the cam screw 129 which is secured in place by means of the lock nut 130.

In operation, the pedal 93 would be depressed and the levers 94 and 105 would be pivoted counterclockwise around the pivot pin 96 as viewed in FIG. 1. This action will cause the valve plunger 83 to be moved inwardly whereby the exhaust valve 87 will close the exhaust passage 86 and the valve rod 88 will unseat the intake valve 89 to permit air under pressure to pass into the valve and through the tubing 70 and into the cylinder 44 and into operative engagement against the piston 58. The rod 43 will be moved upwardly as viewed in FIG. 1 whereby the bell crank 38 will be pivoted around the pivot pin 40. The lever 34 will in turn be moved by the bell crank 38 and will rotate the rocker arm 29 counterclockwise about its pivot pin 33. The rocker arm 29 operates the pressure link 27 downwardly which in turn moves the push rod 21 downwardly for an operation. As the rocker arm 29 is rotated, the fork arm 112 will engage the rod 114 and at a predetermined point in the rotation of the rocker arm 29, the fork arm 112 will engage the stop member 115 whereby the control rod 114 will be lifted upwardly against the pressure of the return spring 128. When the rod 114 is moved upwardly, the stop 127 on the lower end thereof will engage the trip lever 125 and will rotate it counterclockwise as viewed in FIG. 5, whereby the screw 129 will move downwardly and engage the cam nose on the trip bar 103 and pivot this bar clockwise as viewed in FIG. 1. This action will pivot the rear end of the trip bar 103 out of the notch 104 on the lever 105. The lever 105 will be then moved clockwise as viewed in FIG. 1, by means of the action of the return spring 107 and to the position as shown in FIG. 2. The operating plunger 83 will be moved outwardly of the valve body or to the left as viewed in FIG. 1.

When the valve plunger 83 is moved outwardly this action moves the exhaust valve 87 to the left, as viewed in FIG. 1, to unseat this valve and open the valve chamber 81 to the atmosphere. The return spring 90 also moves the intake valve 89 to the closed position to cut off the source of air under pressure. The return spring 65 then moves the piston 58 downwardly back to the rest position as shown in FIG. 1 and the air in the cylinder 45 will be exhausted to the atmosphere through the tubing 70 to the valve chamber 81 and out through the conduit 86.

It will be seen that the press is automatically released at any pre-determined point in its travel depending on the setting of the stop member 115 on the control rod

114. The press is capable of supplying full power up to the release point and a quick release operation is then effected due to the location of the control valve 73 in close proximity to the air cylinder 44. The control system of the present invention eliminates the need for any cushioning means in the air cylinder.

FIGS. 6 and 7 illustrate the press of FIGS. 1 through 5 as provided with a control system which is slightly modified from that of the first embodiment previously described. The corresponding parts of the embodiment of FIGS. 6 and 7 have been marked with the same reference numerals followed by the small letter "a." In this second embodiment the trip lever 125 and cam screw 129 have been replaced with an electrically operated solenoid plunger for actuation of the trip bar 103.

The numeral 131 indicates generally a conventional electrical solenoid mounted in the box 132 on the press body 10a. The solenoid 131 includes the plunger 133 which is adapted to engage the trip bar 103a for releasing the lever 105a whereby the valve 73a will operate in the same manner as valve 73. The plunger 133 is secured to the solenoid armature rod 135 which is adapted to be moved downwardly in the usual manner when the solenoid coil 136 is energized. The solenoid coil 136 would be energized by means of the conductors 137 and 138 which would be connected to any suitable source of electrical power. The flow of power to the solenoid coil 136 would be controlled by means of a suitable micro switch, generally indicated by the numeral 140, which would be provided with two suitable contacts as 139 to make and break the circuit through one of the conduits as 138. As shown in FIG. 6, the lower end 141 of the control rod 114a would normally hold the contacts 139 open, whereby the solenoid 131 would be inoperative. The control rod 114a would be held downwardly in the inoperative position by means of spring 142 bearing against the stop member 143 on the lower end of the rod 114a.

The second embodiment of the invention as shown in FIGS. 6 and 7 operates in substantially the same manner as the previously described first embodiment. The only difference is that when the control rod 114a is moved upwardly by means of the fork arm 112a, the contacts 139 will engage each other since they are spring mounted, and the solenoid coil 136 will be energized. The solenoid armature plunger rod 135 will then be moved downwardly and the plunger 133 will in turn be moved downwardly into operative engagement with the trip bar 103a. The ensuing action is then the same as the aforesaid releasing action of the first embodiment.

While it will be apparent that the preferred embodiments of the invention herein disclosed are well calculated to fulfill the objects above stated, it will be appreciated that the invention is susceptible to modification, variation and change without departing from the proper scope or fair meaning of the subjoined claims.

What I claim is:

1. In an air-powered press, the combination of, a press body; a push rod movably mounted on said press body for carrying a work tool; a rocker arm pivotally mounted on said press body for moving said push rod; an air cylinder mounted on said press body and including a piston and a piston rod connected to said piston and extending through the upper end cover of the cylinder; means connecting said piston rod to said rocker arm for rocking the same when the piston rod is moved outwardly of the cylinder; a spring in said cylinder for normally maintaining said piston in an inoperative position at the lower end of the cylinder; an air flow control valve mounted on said press body adjacent the air cylinder and being connected to the lower end of the cylinder for admitting air under pressure to the cylinder for moving the piston against the pressure of the spring in the cylinder and for

exhausting the air from the cylinder; said air flow control valve including a chamber and exhaust valve for exhausting the chamber to the atmosphere and an alternately operable intake valve for admitting air under pressure into said chamber from a source of pressurized air; a tube connecting said chamber and said cylinder for conducting air under pressure from said chamber to said cylinder for moving said piston and for exhausting said cylinder to the atmosphere through said chamber and exhaust valve; lever means for manually opening said intake valve and closing said exhaust valve, whereby, air under pressure will be admitted into the cylinder to operate the press and rock said rocker arm; and, means for automatically operating said lever means to close said intake valve and open said exhaust valve after a predetermined rocking movement of said rocker arm.

2. In an air-powered press, the combination of, a press body; a push rod movably mounted on said press body for carrying a work tool; a rocker arm pivotally mounted on said press body for moving said push rod; an air cylinder mounted on said press body and including a piston and a piston rod connected to said piston and extending through the upper end cover of the cylinder; means connecting said piston rod to said rocker arm for rocking the same when the piston rod is moved outwardly of the cylinder; a spring in said cylinder for normally maintaining said piston in an inoperative position at the lower end of the cylinder; an air flow control valve mounted on said press body adjacent the air cylinder and being connected to the lower end of the cylinder for admitting air under pressure to the cylinder for moving the piston against the pressure of the spring in the cylinder and for exhausting the air from the cylinder; said air flow control valve including a chamber and exhaust valve for exhausting the chamber to the atmosphere and an alternately operable intake valve for admitting air under pressure into said chamber from a source of pressurized air; a tube connecting said chamber and said cylinder for conducting air under pressure from said chamber to said cylinder for moving said piston and for exhausting said cylinder to the atmosphere through said chamber and exhaust valve; a plunger rod in said air flow control valve for operating the exhaust and intake valves; a first spring biased lever connected to said plunger rod and being normally biased to a first position to open the exhaust valve and close the intake valve; a second spring biased lever releasably connected to said first spring biased lever and being manually operable to move the first spring biased lever to a second position to close the exhaust valve and open the intake valve to admit air under pressure to the cylinder to operate the press and rock said rocker arm; and means operable by said rocker arm for disconnecting said spring biased levers, whereby, said first spring biased lever returns to said first position and said exhaust valve is opened and said intake valve is closed, and, the spring in the air cylinder moves the piston back to the inoperative position.

3. The structure as defined in claim 2, wherein: said means operable by said rocker arm for disconnecting said spring biased levers includes a pivotally mounted trip lever operable when pivoted in one direction to disconnect said spring biased levers, and, a control rod connected to said trip lever and movable by said rocker arm for pivoting the trip lever in said one direction to disconnect said spring biased levers after a predetermined rocking movement of said rocker arm.

4. The structure as defined in claim 2, wherein: said means operable by said rocker arm for disconnecting said spring biased levers includes an electrically operated solenoid for disconnecting said spring biased levers, and, a control rod connected to said solenoid and movable by said rocker arm for energizing the solenoid to disconnect said spring biased levers after a predetermined rocking movement of said rocker arm.

5. The structure as defined in claim 2 wherein said

means connecting said piston rod to said rocker arm includes a pivotally mounted bell crank connected to said piston rod; and, a lever pivotally connecting the one end thereof to said bell crank and at the other end thereof to said rocker arm.

6. In an air-powered press, the combination of, a press body; a push rod movably mounted on said press body for carrying a work tool; a rocker arm pivotally mounted on said press body for moving said push rod; an air cylinder mounted on said press body and including a piston and a piston rod connected to said piston and extending through the upper end cover of the cylinder; means connecting said piston rod to said rocker arm for rocking the same when the piston rod is moved outwardly of the cylinder; a spring in said cylinder for normally maintaining said piston in an inoperative position at the lower end of the cylinder; an air flow control valve mounted on

said press body adjacent the air cylinder and having a chamber operable for admitting air under pressure to the piston end thereof and exhausting air therefrom; a manually operated control means for operating said air valve to admit air under pressure to the cylinder through said chamber; and, means operated by said rocker arm for operating the air flow control valve to exhaust the air from the air cylinder through said chamber.
